HOPPER VIBRATOR

Harold R. Pursel, Philadelphia, Pa., assignor to
The Allen-Sherman-Hoff Company, Philadelphia, Pa., a corporation of Pennsylvania

Application May 17, 1940, Serial No. 335,803

3 Claims. (CL 259—39)

This invention relates to hopper constructions and more particularly to an improved apparatus for preventing arching or bridging of material across the outlet opening of a hopper.

For the storage and handling of divided solids such as ash, sand, powdered coal, etc., hoppers are commonly employed having converging walls and a bottom outlet opening equipped with suitable gate or door. When material is to be discharged from the hopper the bottom gate is opened permitting the ash or the like to flow through the outlet. However, difficulty is experienced due to the tendency of such materials to arch or bridge across the bottom portion of the hopper above the outlet opening with resulting stoppage of the flow through the outlet. To prevent this difficulty it has previously been proposed to install a plate member in the hopper adjacent the bottom thereof and provide means for vibrating the plate to loosen the cohered material and permit it to flow freely through the outlet.

It is among the objects of my present invention to provide a hopper vibrator which does not require sliding engagement of adjacent parts, thereby completely avoiding leaks or openings in the hopper walls. Other objects of my invention include: the provision of a simple, rugged hopper vibrator construction and means for supporting same whereby effective vibration may be imparted to the material in the hopper with a minimum of power; the provision, in a hopper vibrator which is actuated by a rod extending out through the hopper wall, of a flexible leak-proof means for supporting the rod where it passes through the wall; and the provision of a hopper vibrator of the type described which is free from bearing surfaces or the like which are subject to excessive wear due to the abrasive nature of the material handled in such hoppers.

The above and other objects of my invention will appear from the following description of one embodiment thereof, reference being had to the accompanying drawing, in which—

Figure 1 is an elevational view of a hopper bottom shown partly in section and including my improved vibrator mechanism.

Figure 2 is a vertical cross-sectional view taken on line 2—2 of Figure 1.

Figure 3 is an enlarged fragmentary cross-sectional view taken on line 3—3 of Figure 2.

Figure 4 is an enlarged fragmentary cross-sectional view of the sealing and supporting means for the vibrator actuating rod.

In the drawing a conventional form of hopper

is illustrated having sloping side walls 1, 2, 3 and 4 which converge toward the bottom outlet opening 5. A suitable gate 6 is adapted to close the outlet 5 except when it is desired to discharge material therethrough.

My improved vibrator mechanism comprises a plate 7 supported on a transverse rod or shaft 8 which in turn is mounted at its ends in trunnions 9 and 10 carried by the walls 1 and 2 of the hopper. The contour of the plate 7 follows the converging walls 1 and 2 but is spaced therefrom, as is seen in Figure 1. A centrally disposed rib 11 extends down from the upper end of the plate 7 to its lower end and, as is seen in Figures 2 and 3, the inner end of the vibrator operating rod 12 is pivotally attached to the flange or rib 11 by means of a bolt 13.

The operating rod 12 passes freely through a hole 14 in the wall 3 of the hopper, without contact with the wall, into a housing 15 which supports at its outer end a flexible diaphragm 16. An outer clamp ring 17 and suitable screws 18 secure the diaphragm 16 to the end flange 19 of the housing 15 and the central portion of the diaphragm 16 is clamped between the inner clamp ring 20 and a collar member 21 by screws 22. A set screw 23 rigidly secures the collar 21 to the rod 12 and it will be seen that the diaphragm 16 forms an end closure for the housing 15 and also supports the rod 12 and permits it to move freely in horizontal direction without engagement of any part of the hopper structure.

A drain hole 24 extends from the lower part of the housing 15 into the hopper and permits the escape of any liquid which may enter the housing through the aperture 14.

Secured to the outer end of the rod 12 is a vibrator supporting plate 25 on which is mounted a vibrator unit 26. The weight of the vibrator 40 is carried by a flexible strap 27, secured to the upper end of the plate 25 and attached at its upper end to a bracket 28 on the hopper wall 3. The vibrator unit 26, as illustrated, is of the electrical type which includes a vibrating armature 45 adapted to strike a series of rapid blows against the housing of the unit, thus causing a vibratory movement to be imparted to the rod 12 through the plate 25. This movement in turn is transmitted to the plate 7 and serves to prevent or relieve arching of the material in the hopper. The diaphragm 16 permits the vibratory movement of the rod 12 without imposing appreciable resistance thereto and also serves to maintain the plate 7 in its centered position between the hopper walls. It will be understood that other

types of vibrating mechanism, for example, compressed air or steam operated devices, may be employed and, as the weight of the vibrator unit is carried by the flexible strap 27, no load is imposed on the flexible diaphragm 16.

A completely air and fluid tight connection is provided by my diaphragm 16 whereby free vibratory movement of the rod 12 and plate 7 is permitted. Closely fitting sliding supports for the rod 12, which may stick or corrode under the conditions to which this type of apparatus is subjected, are eliminated and, in installations where the hopper is employed for handling mixtures of solids and fluids, leakage around the vibrator operating rod 12 is completely overcome. Furthermore, when a hopper of the type referred to is disposed below a boiler to receive the ash therefrom, the interior of the hopper is subjected to boiler draft conditions. In such cases the pressure in the hopper is usually below atmospheric and my improved hopper vibrator construction prevents the infiltration of air into the hopper and furnace combustion chamber. When the hopper contains gas under greater than atmospheric pressure my structure also effectively prevents the escape of such gas to the atmosphere and thus I have provided a hopper vibrator which is particularly well adapted for use with boiler ash hoppers and the like which operate under other than atmospheric pressure.

Although I have described the illustrated embodiment of my invention in considerable detail it will be understood by those skilled in the art that variations and modifications may be made in the form of apparatus employed without departing from the spirit of my invention. I do not, therefore, wish to be limited to the specific embodiment of my hopper vibrator herein shown and described, but claim as my invention all forms thereof coming within the scope of the appended claims.

I claim:

1. In a hopper having walls and a bottom outlet opening and a plate pivotally supported in said hopper above said bottom outlet opening, a rod

secured to said plate and extending freely through an aperture in a hopper wall, a flexible diaphragm carried by said hopper wall, rigid connections between said diaphragm and said rod, and means, disposed externally of said diaphragm, for imparting vibratory movement to said rod and diaphragm, said last named means including a self contained vibrating unit connected to impart vibratory movement to said diaphragm and a flexible supporting strap secured at one end to said hopper wall and adapted to carry the weight of the vibrating mechanism without restricting the vibratory movement thereof.

2. In a hopper having downwardly extending walls and a bottom outlet opening and a plate pivotally supported in said hopper and spaced relative to the walls thereof, an operating rod connected to said plate and extending freely through an opening in one of the hopper walls, a tubular housing surrounding said opening and rod, a flexible diaphragm closing one end of said housing and secured to said rod for supporting and permitting vibratory movement of said rod, a vibrating unit connected to said rod outside of said housing for imparting vibratory movement to the rod, and means secured to the hopper and supporting said vibrating unit, said means being capable of flexing toward and away from said hopper with the vibratory movement of said rod.

3. In a hopper having downwardly extending walls and a bottom outlet opening and a plate pivotally supported in said hopper above said bottom outlet opening, a rod secured to said plate and extending freely through an opening in a hopper wall, a flexible diaphragm carried by said hopper wall outside of said opening and connected to said rod for supporting the latter, a vibrating unit secured to said rod outside of said diaphragm for imparting vibratory movement to said rod and diaphragm, and flexible means secured to the hopper and supporting the weight of the vibrating means without substantially restricting the vibratory movement thereof.

HAROLD R. PURSEL.
